UNITED STATES PATENT OFFICE.

JOHN R. MOFFITT, OF PIQUA, OHIO.

GRAIN-SEPARATOR.

Specification of Letters Patent No. 26,283, dated November 29, 1859.

To all whom it may concern:

Be it known that I, JOHN R. MOFFITT, of Piqua, Miami county, Ohio, have invented a certain new and useful Improvement in 5 Grain-Separators; and I hereby declare the following to be a full and exact description of the same, reference being had to the accompanying drawings, making part of this specification.

10 The said improvement consists in a peculiar arrangement and adaptation of screen, and reversible delivery spout to separate extraneous matters from the grain after the action of the winnowing apparatus.

15 The accompanying drawings illustrate the invention applied to an "overshot" threshing machine, or one in which the concave is placed above the cylinder.

Figure 1 is a perspective view of the machine. Fig. 2 is a detached perspective view of the screen and reversible spout on a larger scale. Fig. 3 is a vertical transverse section of the shoe screen and spout at $\alpha\alpha$ Fig. 1.

20 The frame A cylinder B straw carrier F elevator O and winnowing apparatus H 1 may be of any suitable construction.

M is the spout through which clean grain is delivered from the machine.

25 N is a screen which is fixed in position above or within the spout M, so as to move in conjunction therewith. The screen and spout are suspended beneath the shoe in the following manner: P P' are screw bolts

30 which may either be attached directly to the side of the shoe or pass through hangers attached thereto—the former plan being preferred as more simple. At one end the frame of the spout, and that of the screen

35 are made sufficiently thin, and are pierced to receive the bolt P which passes through both, and supports them by means of a screw nut p. Q is a yoke which is attached to the spout M in the manner shown, in the

40 proper position to bring it immediately beneath one side of the shoe when the spout is in position. The screen is placed above the spout and within the yoke in the manner exhibited so that the screw bolt P' being at-

45 tached to the yoke by means of the nut p' supports both spout and screen. In practice the bolts P and P' are permanently fixed to the sides of the shoe, and are made of equal length being the length necessary to

55 pass through the rear ends of both spout and screen as seen at P. The reversal of the spout is effected by removing the nuts p p', turning the spout and screen end for end and replacing them in position so that the bolt which formerly sustained the rear 60 end of the spout now sustains the yoke and vice versa. In the construction shown in the drawings it would be needful to reverse the bolts P and P' also; but these variations are immaterial to the principle of the in- 65 vention.

70 In the customary winnowing apparatus as adapted to threshing machines the action of the shoe screen working in conjunction with a blast fails to separate those parts of the refuse which are of nearly equal weight with the grain because a strength of blast which would blow them away would remove grain as well. For this reason grain thus intermixed is often conveyed from the thresher 75 and winnower to a separate mill where it can be subjected to the screening action for a longer period and apart from the wind. By my improvement the screening apparatus is arranged and operated in connection 80 with the shoe in such a manner as to subject the grain to its final screening apart from the fan blast, immediately prior to its discharge from the machine and the apparatus is so arranged as to adapt it to deliver on 85 either side which direction of the wind or circumstances of the location may render desirable.

90 I do not wish to be understood as claiming broadly under this application every apparatus operating in connection with a threshing machine to screen grain apart from the action of the fan blast, this being accomplished by the apparatus described in Division C of my patent for grain separator dated 30 November 1852, and reissued 95 17th May 1859. Neither do I claim broadly to be the inventor of a combination of screen and spout adapted to separate articles of different fineness and deposit them automatically in separate receptacles. My claim is 100 confined to a specific arrangement, whereby the screen and spout are adapted to operate in connection with a grain separating machine in the manner herein described, and I do not claim such devices otherwise than in the said connection.

105 The following is what I claim as new and

of my invention herein and desire to secure by Letters Patent.

In the described combination with a reversible spout adapted to discharge grain at either side of a threshing and separating machine, I claim the screen N, placed within or above the said spout and operated by the motion of the shoe for the purpose of

screening grain after the action of the winnowing apparatus.

In testimony of which invention, I hereunto set my hand.

J. R. MOFFITT.
